UNITED STATES PATENT OFFICE.

ROBERT J. KUHL, OF ST. LOUIS, MISSOURI, ASSIGNOR TO AMERICAN CAR AND FOUNDRY COMPANY, OF NEW YORK, N. Y., A CORPORATION OF NEW JERSEY.

REFRIGERATOR-CAR CONSTRUCTION.

Application filed January 6, 1925. Serial No. 904.

In the drawings:

Fig. 1 is a partial horizontal section of a car body constructed in accordance with this invention;

5 Fig. 2 is a transverse vertical section taken on the line 2—2 of Fig. 1;

Fig. 3 is a fragmentary sectional view drawn to a larger scale and taken at one of the side posts shown in Fig. 1;

10 Fig. 4 is a perspective view of a section of the insulated side wall of Fig. 1 shown detached from the car body;

Fig. 5 is a perspective view of one of the removable key posts shown in Fig. 1; and

15 Figs. 6 and 7 are horizontal sections taken through side posts and showing key posts and wall sections of modified constructions.

In the making of repairs to damaged car side walls it is frequently necessary to remove the entire side of the car from the door post to the adjacent corner post in order to make a proper repair to a particular part of the side wall and in the case of insulated or refrigerator cars this necessitates the removal and replacing of the insulation also. A car side wall built of sections which could be removed independently for repair or replacement would greatly reduce the amount of the side wall that must be removed in order to repair any particular part and would greatly expedite the making of such repairs. A further advantage would be obtained in the making and repairing of the sections as the work could be done more expeditiously and better when done at a bench than when done in position on the car.

It is an object of this invention to provide an improved wall construction for cars, and more particularly to provide an improved wall construction for insulated or refrigerator cars comprising wall sections which may be applied as units and which will permit of a single unit being repaired or replaced without necessitating removal or reconstruction of the adjacent sections. It is also an object of this invention to provide a means by which the sections may be readily and securely held in position and which will permit of ready removal for repair and replacement.

In the drawings the invention is shown as applied to a refrigerator car having insulated walls, although it may be applied to cars of other description. The car shown

comprises an underframe 1 having bolsters 2, cross bearers 3 and side sills 4 of any desired construction. To the underframe are secured the side posts 5 which carry the side plates 6. Mounted on the underframe 60 are the side nailing strips 8 to which is secured an insulated floor 10 of any desired construction. To the outsides of the nailing strips 8 are secured the bottom courses 12 of the side sheathing which lie between 65 the side posts 5 and the nailing strips 8. To the side plates 6 are secured an insulated ceiling 14 and a roof 16 of any desired construction. It will be noted that the floor 10 and the nailing strips 8 provide a continuous 70 flat surface extending to the bottom courses 12 of the side sheathing and that the ceiling 14 provides a flat surface extending to the side plates 6, both the floor and the ceiling extending to the ends of the 75 car. At the ends of the car the floor and ceiling are joined by insulated end walls 18 which are built in the usual manner and at their sides are joined to end sections 20 of the side walls which are also constructed 80 in the usual manner and which extend from the end posts 22 to the adjacent side posts 5.

From the side posts 5 adjacent to the ends of the car to the posts forming the door openings (not shown), the side walls are 85 formed of independently fabricated sections 24 which extend between adjacent side posts 5 and from the floor 10 to the ceiling 14, the sections being secured to the side posts 5 by key posts 26 of insulating material 90 and preferably of wood. As shown in Figs. 2, 3 and 4, the sections 24 comprise a rectangular frame 27 of insulating material and preferably of wood having vertical members 28 and horizontal members 30 to 95 which are secured layers 31 of a suitable insulating material between which is placed insulating packing of any suitable material, shown in Fig. 3 as comprising two layers 32 of a material such as hair felt. To the 100 frame 27 and overlying the insulating layers 31 are secured the outer sheathing 34 and the inner lining 35, both the outer sheathing 34 and the inner lining 35 are shown formed 105 of wood strips though other suitable material may be used. The outer sheathing, at the top, and the layers of insulation and inner lining are finished flush with the horizontal members 30 of the frame 27, while the outer sheathing 34 and adjacent layer 110

of insulation 31 project beyond the vertical members 28 of the frame and the other insulating layer 31 and lining 35 do not extend quite to the outer surface of the vertical members 28. The stepping back of the parts of the wall section along the vertical edges of the same provides shoulders which are engaged by shoulders formed on a complementary shaped wood key post 26 which is secured to the side posts 5 by bolts 36.

In the modified construction shown in Fig. 6, the wall sections are shown as comprising the outer sheathing 34 and inner lining 35 secured to a frame 27' and confining between them an insulation 40. The vertical members 28' of the frame are set back slightly from the vertical edges of the outer sheathing 34 and project slightly beyond the vertical edges of the inner lining 35 and are tapered to be engaged by a complementary formed wood key post 41 which has faces engaging with the shoulders formed along the vertical edges of the wall sections and inclined faces engaging with the inclined faces of the vertical frame members 28'. In this construction, the key post 41 is formed of a tapered member 42 which receives the bolt 43 by which it is secured to the side post 5, and a strip 44 is secured to the member 42 by screws 45 and covering the heads of the bolts 43.

In the modified construction shown in Fig. 7, the wall sections comprise the outer sheathing 34 and the inner lining 35 which are secured to the frame 27'' and between which are confined the insulation 50 and 51. In this construction the vertical members 28'' of the frame are shaped to receive the channel-shaped key post 53 having flanges 54 which are secured to the frame members 28'' by screws 55 which also secure cover strips 56 and insulation 57 to the key posts, the key posts being secured to the side posts by the bolts 58. In this construction, as in the other constructions, shoulders or inclined faces are formed along the vertical edges of the wall sections which are engaged by the key posts so that the wall sections are securely held to the side posts by the key posts.

In constructing a car in accordance with this invention, the car frame floor 10, ceiling 14, end wall 18 and end sections 20 of the side walls are constructed in the usual manner, except that the ends of the sections 20 adjacent the side posts 5 are fashioned to be engaged by the key posts 26. Sections 24 are then placed in position against the inner faces of side posts 5 with the lower edges of the bottom courses 60 of the outer sheathing on the sections 24 engaging with the upper edges of the lower course 12 of the side sheathing. It will be noted that the meeting edges of the sheathing courses 12 and 60 are beveled to make a tight joint

and that the upper courses 61 of the sheathing are gained out to receive the side plates 6. The key posts are then placed in position and secured to the side posts 5 by the bolts, and in the case of the modifications 70 shown in Figs. 6 and 7, the strips 44 and 56 are then secured in place to complete the key posts.

To replace a section, the key posts at opposite sides of the section to be replaced are 75 released from the side posts and withdrawn to the inside of the car, whereupon the section between these posts is free to be removed to the inside of the car and replaced by another section which is inserted in position 80 against the side posts 5 from the inside of the car.

What is claimed is:

1. In a car, a frame comprising fixed posts, an insulating wall comprising a plurality of formed removable insulating sections and removable key posts secured to said fixed posts and securing said sections in position.

2. In a car, a wall comprising fixed posts secured to the outside of the car under-frame, key posts detachably secured to said fixed posts and independently formed wall sections secured between said fixed and key posts and removable inwardly.

3. In a car, an insulated wall comprising fixed posts, key posts detachably secured to said fixed posts and insulated wall sections removably secured by said posts.

4. In a car, a wall comprising fixed posts, removable formed insulating wall sections engaging said fixed posts and removable key posts fitting between said sections and securing said sections to said fixed posts.

5. In a car, a wall comprising fixed outside posts, wall sections engaging said fixed posts and removable key posts located between the wall sections and securing said wall sections to said fixed posts, said key posts being removable from the inside of the car to effect removal of the wall sections from the inside of the car.

6. In a car, a wall comprising fixed posts, removable insulating wall sections engaging the inner faces of said posts and key posts 115 detachably secured to said fixed posts and engaging said insulating wall sections to secure said wall sections in place.

7. In a car, a body frame having fixed posts, wall sections engaging said fixed posts, and key posts secured to said fixed posts and securing said wall sections in place, said wall sections and key posts being removable inwardly of the body frame.

8. In a car, a body frame having fixed 120 posts, insulating wall sections comprising inner and outer sheathing and an insulation lining and key posts removably securing said wall sections against said fixed posts.

9. In a car, a body frame having fixed 125

metal posts, independently formed insulating wall sections and movable posts forming keys between said wall sections and securing said wall sections to said fixed posts.

5 10. In a car, a wall comprising fixed posts, removable insulating wall sections and removable posts securing said insulating wall sections to said fixed posts.

10 11. In a car, a wall comprising fixed posts, removable insulating wall sections, and removable key posts positioned between and overlapping the ends of said insulating sections for securing the sections to said fixed posts.

15 12. In a car, a wall comprising fixed posts, wall sections engaging said fixed posts and positioned between the floor and ceiling of the car, and key posts engaging and detachably secured to said fixed posts, said key posts being positioned between the floor and the ceiling of the car and overlapping end portions of the wall sections.

20 25 13. In a car, a wall comprising fixed posts, wall sections engaging said fixed posts and having the ends thereof offset in stepped manner, and key posts engaging and detachably secured to said fixed posts, said key posts being positioned between the wall sections and being shaped to fit the offset ends 30 of the wall sections for holding such sections securely in position.

25 30 14. In a refrigerator car, a wall comprising fixed posts, insulating wall sections positioned between the floor and ceiling of the car and having inner and outer sheathing separated by insulating material, and key posts engaging and secured to said fixed posts, said key posts being positioned be-

tween the floor and ceiling of the car and overlapping the ends of said wall sections 40 for holding the wall sections in position.

15 45 15. In a refrigerator car, a wall section comprising fixed posts carried by the car underframe, insulating wall sections having a frame with inner and outer sheathing and insulating layers secured thereto, said wall sections being positioned between the floor and the ceiling of the car, and key posts detachably secured to the fixed posts and overlapping the ends of said wall sections. 50

16 55 16. In a refrigerator car, a wall comprising fixed posts secured to the car underframe, insulating sections comprising outer and inner sheathing separated by insulating layers and a frame work, said frame work carrying insulating material between said insulating layers, and key posts positioned between and overlapping the ends of said insulating sections for securing the insulating sections to said fixed posts. 60

17 65 17. In a refrigerator car, a wall comprising fixed posts secured to the underframe below the car floor and extending to side plates above the car ceiling, wall sections engaging the inside of said fixed posts and positioned between the floor and the ceiling of the car, and key posts secured to and engaging the fixed posts and positioned between the wall sections, said key posts overlapping the ends of said wall sections for 70 holding them in position against the fixed posts.

In witness whereof I have hereunto set my hand.

ROBERT J. KUHL.
